DESIGN FOR A BUMPER BAR

Donald T. Gleason and William E. Saxton, Coraopolis, Pa., assignors to Standard Steel Spring Company, Coraopolis, Pa., a corporation of Pennsylvania

Application July 21, 1936, Serial No. 63,972

Term of patent 7 years

To all whom it may concern:

Be it known that we, Donald T. Gleason and William E. Saxton, citizens of the United States and residing at Coraopolis, in the county of Allegheny and State of Pennsylvania, have invented a new, original, and ornamental Design for a Bumper Bar, of which the following is a specification, reference being had to the accompanying drawing, forming a part thereof, wherein:

Figure 1 is a plan view of a bumper bar showing our new design; Figure 2 is a front elevational view thereof, and Figure 3 is a sectional view taken on line III—III of Figure 2.

We claim:

The ornamental design for a bumper bar substantially as shown.

DONALD T. GLEASON.
WILLIAM E. SAXTON.
